CHARLES HENRY FOX, OF BAKERSFIELD, CALIFORNIA.

PUMP.

1,103,190.

Specification of Letters Patent. Patented July 14, 1914.

Continuation of application Serial No. 386,309, filed July 30, 1907. This application filed August 14, 1912. Serial No. 715,110.

To all whom it may concern:

Be it known that I, CHARLES H. Fox, a citizen of the United States, residing at Bakersfield, in the county of Kern and State of California, have invented a new and useful Pump, of which the following is a specification.

This invention has reference to improvements in pumps, and its object is to provide 10 a means for elevating water directly by the energy developed by the burning of an explosive mixture, especially an explosive mixture of a hydrocarbon and air.

The present invention is designed more 15 particularly for the elevation of water from wells to the surface and to any desired point above the surface of the ground, and to this end the invention comprises one or more explosion chambers to be located at a suitable 20 depth in the well, such depth being as close to the bottom of the well as circumstances will permit, and leading from the explosion chamber in communication therewith is a water conducting pipe continued 25 to the top of the ground and to any suitable point for the disposition of the elevated water. Provision is also made for introducing an explosive mixture into the explosion chamber near the bottom of the 30 well and the ignition of such explosive mixture in a manner to cause the great volume of gases so formed to be projected into the pipe provided for the outflow of water, whereby the gases serve to lift the water to 35 the surface. By a suitable arrangement at the surface of the ground the introduction of the explosive mixture into the explosion chamber or chambers and the firing of the explosive mixture may be controlled as may 40 be needed.

The invention will be best understood from a consideration of the following detailed description, taken in connection with the accompanying drawings forming a part 45 of this specification, with the further understanding that while the drawings show practical forms of the invention, the latter is susceptible of other practical embodiments and may, therefore, be changed and modified 50 so long as such changes and modifications mark no material departure from the salient features of the invention.

In the drawings:—Figure 1 is a view showing the lower end of a well and illustrating 55 an embodiment of the invention.

Fig. 2 is a section on the line 2—2 of Fig. 1, but drawn to a larger scale. Fig. 3 is a longitudinal diametric section of one of the explosion cylinders employed in the structure shown in Figs. 1 and 2. Fig. 4 is a 60 vertical section through the explosion chambers of a double acting pump structure embodying the features of Fig. 1 and also illustrating a means for lubricating the moving parts. Fig. 5 is a vertical central 65 section through a portion of the explosion chamber of Fig. 4 showing the exhaust conduit but omitting the piston from the explosion chamber. Fig. 6 is a plan view of the structure shown in Fig. 5 with the explosion chamber shown in cross section and distant parts omitted.

Referring to the drawings, there is shown a well casing 1 which may be taken as indicative of any suitable well assumed to be 75 sunk to a suitable depth and to contain a body of water, although for clearness of illustration no water is indicated in the drawings.

Within the well casing there is located a 80 pipe 42 which may be considered as extending to a sufficient depth below the normal surface of water contained in the well and secured to the lower end of the pipe 42 and grouped thereabout are cylinders 43 shown 85 as four in number, but this particular number is not obligatory. Each cylinder is provided at the ends with heads 44, which since the cylinders are usually placed upright may be called the upper and lower heads 90 of these cylinders. At a mid point of each cylinder there is an exhaust pipe or duct 45 communicating with a common outlet 46 extending upwardly into the pipe 42 and there freely open. Within each cylinder there is 95 lodged a reciprocating member shown in the drawings in the form of a piston 47 provided with packing rings 48, and since the cylinders are designed to receive explosive mixtures the piston 47 may be in effect similar to the pistons of ordinary explosion engines, but the pistons 47 have no piston rods or pitmen. The reciprocating members or pistons 47 perform the functions 100 of compressors and valves, as will herein-after appear, and are capable of moving lengthwise of the cylinders with requisite freedom, although they should fit the cylinders sufficiently tight to prevent undue leakage about them.

Leading into the well outside the pipe 42 is a pipe 23^a having branches 49 opening through both the upper and lower heads of the cylinders 43. Each pipe 23 and 23^a is provided with a check valve 50 designed to prevent back-firing. Each cylinder 43 has near each end a spark plug 41^a fed by conductors 39^a carried through pipes 40^a, such conductors coming from a source of 10 suitable current supply such as is customary to use in connection with explosion engines, there being in the structure shown in Figs. 3 and 4 as many pipes 40^a and sets of conductors as there are cylinders 43, this providing for the energization of the spark plugs in such order as may seem advisable. Each upper and lower head of each cylinder is provided with a pet cock 50^a under the control of a rod 51, the arrangement being 15 such that any one or more of the pet cocks may be opened as may be desired for a purpose which will presently appear.

Let it be assumed that the structure shown is at rest, the pistons 47 will gravitate to the bottom of the cylinders and the upper ends of the cylinders will become full of water through the exhaust passages 45. Now, by opening the upper pet cocks and forcing an explosive mixture through the 20 pipe 23^a it will flow into the cylinders and the ends of the cylinders below the pistons will become filled with the explosive mixture, causing the pistons to rise and force the water out through the pet cocks in the upper 25 heads of the cylinders. By now energizing the spark plugs in proper order explosions will occur forcing the pistons toward the ends of the cylinders remote from that in which the explosion takes place and 30 the pet cocks being closed a cycle of operations is established, so that by causing the explosions to occur in order the pistons will reciprocate in proper relation one to the other to produce through the outlet 46 a 35 rapid succession of forceful streams of gases which will serve to lift water within the pipe 42 to the surface of the ground, and these explosions may be made to follow each other with sufficient rapidity to practically 40 make the operation continuous.

Where there are submerged moving parts subjected to the action of gases of explosion, as in the structure shown in Fig. 1, it is of advantage to supply lubricant to 45 such moving parts, and in Fig. 4 there is disclosed a means for so doing with some slight modifications in the structure of the movable piston, and of the cylinder inclosing the explosion chambers. In this structure there is a cylinder 43^a in which a piston 47^a may move freely under the action of the exploding gases. At each end of the cylinder 43^a there is a reduced extension 50 of the bore of the cylinder, and this extension receives a cap or head 53 to which is

connected the inlet pipe 49^a for the fuel. The cap 53 carries a valve 54 normally seated in an appropriate valve seat formed in the head and having a stem 55 extending into the conduit 49^a for an appropriate distance. The extent of movement of the valve is limited by a pin 56 traversing the stem 55. The valve stem 55 is carried into a branch 57 of a T 58 located within the conduit or pipe 49^a and from the other branches 70 of the T lead pipes 59 through the conduit 49^a to respective check valves 60, 60^a. The valve 60, opening toward the T 58 is connected to a pipe 61 leading to the surface of the ground and there supplied with an appropriate quantity of lubricant. The other valve 60^a, opening away from the T 58 is connected to a pipe 62 with branches 75 63 tapped into the cylinder 43^a in the path of the piston 47^a, so as to feed lubricant thereto. The valve stem 55, moving in the central branch of the T 58, acts as a pump for the lubricant, the valves 60 and 60^a serving as pump valves. The other end of the cylinder may be similarly provided with a 80 valve 54 and associated parts and connected up to the supply pipe 61 and a pipe 62^a leading therefrom is connected by branches 63^a to the cylinder to also supply lubricant thereto, so that the piston 47^a may receive 85 lubricant from opposite sides. Since the two ends of the cylinder are alike it is deemed unnecessary to illustrate the structures at more than one end of the cylinder. 90

The piston in the structure shown in Fig. 4 is provided at each end with an axially extended stem 64, while in that portion of the cylinder having the reduced bore 52 the walls are provided with a tapped passage 65 receiving a spark plug 41^b which 100 may be similar to the spark plugs of the other structures except that in this case the spark plug has terminals 66 so located as to be within electrical striking distance of the appropriate stem 64 when the latter is 105 brought into proper relation to the terminals 66. By supplying the spark plug with an electric current of sufficiently high tension sparks will pass from one terminal 66 to the stem 64 and from the latter to the other terminal 66, thus assuring the ignition 110 of the explosive mixture. 115

It is of advantage to avoid the entrance of water into the cylinder, wherefore the cylinder may be provided with an outlet 45^a terminating at its outer end in a valve seat 67 to which a valve 68 is adapted, this valve being preferably conical in shape and provided with a directing stem 69 carried by a cage 70 in turn made fast to the discharge 120 end of the exhaust conduit. By this means the exhaust conduit is closed except when gases of explosion are passing therethrough, and under these circumstances the pressure 125 of these gases is too great to permit water 130

to enter the exhaust conduit. When the pressure lowers sufficiently to permit the entrance of water into the exhaust conduit the valve 68 drops to the seat 67 and so closes the conduit against the entrance of water. It will be understood that whether one or a number of cylinders are employed the exit end of the exhaust conduit is provided with a valve preventing the entrance 10 of water.

It will be understood, of course, that the structures of Figs. 4, 5 and 6 are to be associated with the water pipe 42 and that the cylinders 47^a may be multiplied in the 15 same manner as shown in Fig. 1.

This application is a continuation of my application No. 386,309, filed July 30, 1907, for improvements in pumps in so far as it has features in common therewith.

20 In both applications a free piston in the cylinder and having no exterior connections is driven by the ignition of an explosive charge to cause the elevation of water, the cylinder with the piston being located in a 25 well or reservoir from which the water is to be raised.

What is claimed is:—

1. An apparatus for raising water from wells, comprising a water pipe of a length to 30 extend from near the bottom of the well below the surface of water therein to near the top of the well, a cylinder immersed in the water in the well and provided with means of communication with the water pipe, a 35 reciprocatory piston within the cylinder movable into covering and uncovering relation to said means of communication, a valve for said means of communication closing toward the cylinder, and means for 40 causing ignition of an explosive mixture in the cylinder to actuate the piston and to be projected into the water pipe for the elevation of the water by the combined effect of the buoyancy of the gas so formed and the 45 force of the explosion.

2. In an apparatus for elevating water, a water pipe, an explosion chamber provided with means for causing the explosion of explosive mixtures in the chamber, means for 50 directing the gases so formed from the explosion chamber into the water pipe at a low point in the latter, a reciprocatory member in the explosion chamber and related to the means for directing the gases to the water pipe to control the flow of such gases, and means for preventing the flow of water 55 into the explosion chamber when the force of the explosion is exhausted.

3. In an apparatus for raising water, a 60 water pipe, power means including an explosion chamber, a reciprocatory member movable therein, and connections controlled by the reciprocatory member between the explosion chamber and the water pipe for

directing gases of explosion into the latter, 65 and means for preventing the return flow of water toward the explosion chamber.

4. A means for the elevation of water from wells, comprising a water pipe, a cylinder supported at the lower end thereof, a 70 piston within the cylinder movable lengthwise thereof, an exhaust duct leading from an intermediate point of the cylinder and opening into the pipe in an upward direction, means for filling the opposite ends of 75 the cylinder with an explosive mixture, and means for igniting the explosive mixture at opposite ends of the cylinder.

5. A means for the elevation of water from wells comprising a pipe adapted to be 80 lowered into the well to a point below the water level of the well, a group of cylinders associated with the lower end of the pipe, a reciprocatory piston in each cylinder, an 85 exhaust duct communicating with each cylinder at a mid point thereof and united into a common exhaust duct directed upwardly lengthwise of the pipe and opening thereinto, a common supply for the cylinders for directing explosive mixtures to opposite ends thereof, spark plugs at opposite 90 ends of the cylinders, means for energizing the spark plugs, valves at opposite ends of the cylinders, and means operable from the top of the well for opening and closing 95 the valve at will.

6. A means for the elevation of water from wells, comprising a water pipe, a cylinder supported at the lower end thereof, a 100 piston within the cylinder movable lengthwise thereof, an exhaust duct leading from the intermediate portion of the cylinder and opening from the pipe in an upward direction and there provided with a valve for preventing the entrance of water into the 105 exhaust duct, means for supplying opposite ends of the cylinder with an explosive mixture, and means for there igniting the explosive mixture.

7. A means for the elevation of water 110 from wells, comprising a water pipe, a cylinder supported at the lower end thereof, a piston movable lengthwise of the cylinder, an exhaust duct leading from the cylinder 115 into the water pipe, means for supplying an explosive mixture to the cylinder, and means for igniting the explosive mixture comprising a conducting stem on the cylinder and electric terminals related to the stem to be within such distance thereof at one point in 120 the movement of the piston as to cause sparks to pass between the terminals and the conducting stem.

8. A means for the elevation of water 125 from wells, comprising a water pipe, a cylinder supported at the lower end thereof, a piston within the cylinder movable lengthwise thereof, means for causing explosions

- to occur within the cylinder to actuate the piston, and means for supplying lubricant to the piston from the surface of the ground.
9. A means for the elevation of water from wells, comprising a water pipe, a cylinder supported at the lower end thereof and provided with an inlet duct for an explosive mixture, a piston within the cylinder movable under the action of the explosive mixture, and means for supplying lubricant to the piston comprising lubricant ducts leading to the piston and including a lubricant pump responsive to the inflow of explosive mixture to the cylinder and to the pressure of exploded gases within the cylinder.
10. A means for the elevation of water comprising a water pipe, a cylinder connected thereto at a point from which the water is to be elevated, a piston within the cylinder movable lengthwise thereof and free from exterior connections, an exhaust duct leading from an intermediate point of the cylinder and opening into the pipe in an upward direction, means for supplying an explosive mixture to opposite ends of the cylinder, and means for igniting the explosive mixture at the opposite ends of the cylinder.

11. A water elevator comprising a water pipe, a cylinder connected to the water pipe at a point from which the water is to be elevated, a reciprocable member within the cylinder, an exhaust duct leading from the cylinder and controlled by the reciprocable member, means for supplying an explosive mixture to opposite ends of the cylinder, and igniting means for the explosive mixture controlled by the reciprocable member.

12. A water elevator, comprising a water pipe, a cylinder, a connection between an intermediate part of the cylinder and the water pipe at a low point in the latter, a freely reciprocatory member within the cylinder movable across the connection between the cylinder and water pipe to opposite sides of such connection, and means for causing the introduction and explosion of explosive mixtures in the cylinder on opposite sides of the reciprocatory member.

In testimony, that I claim the foregoing as my own, I have hereto affixed my signature in the presence of two witnesses.
